(57) **CLAIM**

The ornamental design for a movable camera module for portable electronic device, as shown and described.

DESCRIPTION

FIG. 1 is a back perspective view illustrating a movable camera module for portable electronic device showing my new design, shown in a retracted configuration;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof;

FIG. 8 is a front perspective view thereof, shown in an extended configuration;

FIG. 9 is a back view thereof;

FIG. 10 is a front view thereof;

FIG. 11 is a side view thereof;

FIG. 12 is another side view thereof;

FIG. 13 is a top view thereof;

FIG. 14 is a bottom view thereof;

FIG. 15 is another front perspective view, shown in a partially folded configuration; and,

FIG. 16 is another front perspective view, shown in an extended configuration.

The broken lines on the surface of the design represent unclaimed portions of the camera.

The broken lines depicting a desk surface and a keyboard in FIGS. 15 and 16 represent unclaimed environmental structure.

1 Claim, 12 Drawing Sheets
